UNITED STATES PATENT OFFICE.

JOHN J. TEMPLE, OF KALAMAZOO, MICHIGAN.

ICE-CREEPER.

SPECIFICATION forming part of Letters Patent No. 313,898, dated March 17, 1885.

Application filed August 2, 1884. (No model.)

To all whom it may concern:

Be it known that I, JOHN J. TEMPLE, a citizen of the United States, residing at Kalamazoo, county of Kalamazoo, State of Michigan, 5 have invented a new and useful Ice-Creeper, of which the following is a specification.

This invention has for its object certain improvements, hereinafter described and claimed.

10 In the drawings forming a part of this specification, Figure 1 shows a boot-heel with the device connected therewith in perspective; Fig. 2, a plan view; and Fig. 3 is a detached part of Fig. 2 in enlarged perspective.

15 The device consists in a two-part frame composed of bars *i e*, connected by internally-threaded cross bars *e e*, said parts *i c* being provided with the spurred arms *a a*, adapted to engage the edge of the sole or heel of a boot 20 or shoe. The bars *i i* are provided with perforated side extensions, and the bars *c c* are provided with rods *r r*, adapted to enter said side extensions, as in Fig. 1, to keep the parts of the frame in proper relation to each other 25 and the sole of the boot or shoe. *v v* are the spurs to prevent slipping. The parts of the frame are held together in an adjustable manner by the right and left threaded rod *B*, which screws into the internally-threaded cross-bars 30 *e e*.

By turning the rod *B* by means of a key, *f*, connected with the square end, the frame is made laterally wider or narrower, according to the given size of the heel or sole, and by

this means as well the spurred arms *a a* are 35 clamped against the edges of the sole. During said action the rods *r r* play freely in or out of the recessed extensions of bars *i i*.

In Fig. 3 the key *f* is shown having a spurred end, *S*, and a threaded end, *y*. Said threaded 40 end may be screwed into a threaded hole, with which one of the arms *a* is provided with, and when thus adjusted and the creeper connected with the heel, as in Fig. 2, the spurred key can be used as a riding-spur. 45

Having thus described my invention, what I claim as new is—

1. An ice-creeper consisting of the frame parts, as described, provided with threaded 50 holes to receive the connecting-rod, perforated side extensions, rods adapted to play therein, spurred arms and spurs for engaging the ice, and a right and left threaded rod adjustably connecting the frame parts, substantially as set forth. 55

2. An ice-creeper provided with spurred arms for clamping the sole and spurs for engaging the ice, one of said arms being provided with a threaded hole for the connection therewith of the threaded end of the spurred 60 key, substantially as set forth.

In testimony of the foregoing I have hereunto subscribed my name in presence of two witnesses.

JOHN J. TEMPLE.
